Primary Examiner — T Chase Nelson*Assistant Examiner* — Sydney Margaret Parsley(74) *Attorney, Agent, or Firm* — Birchwood IP(57) **CLAIM**

The ornamental design for an acoustic panel, as shown and described.

DESCRIPTION

FIG. 1 is a front, top and left side perspective view of an acoustic panel, showing my new design;

FIG. 2 is a front elevational view thereof;

FIG. 3 is a rear elevational view thereof;

FIG. 4 is a left side elevational view thereof;

FIG. 5 is a right-side elevational view thereof;

FIG. 6 is a top plan view thereof; and

FIG. 7 is a bottom plan view thereof; and,

FIG. 8 is a sectional view thereof taken along line **8-8** of FIG. 2.

The broken line in FIG. 2 depicts the sectional view indicator of the FIG. 8 view and forms no part of the claimed design.
